(57) **CLAIM**

The ornamental design for the product holder attachment for shopping cart, as shown and described.

DESCRIPTION

FIG. 1 is a perspective view of a first embodiment of the product holder attachment for shopping cart design of the present invention;

FIG. 2 is a front view of a first embodiment of the product holder attachment for shopping cart design of the present invention;

FIG. 3 is a rear view of a first embodiment of the product holder attachment for shopping cart design of the present invention;

FIG. 4 is a first side view of a first embodiment of the product holder attachment for shopping cart design of the present invention;

FIG. 5 is a second side view of a first embodiment of the product holder attachment for shopping cart design of the present invention;

FIG. 6 is a top view of a first embodiment of the product holder attachment for shopping cart design of the present invention;

FIG. 7 is a bottom view of a first embodiment of the product holder attachment for shopping cart design of the present invention;

FIG. 8 is a perspective view of a second embodiment of the product holder attachment for shopping cart design of the present invention;
